UNITED STATES PATENT OFFICE

LESLIE T. PETERSEN, OF DENISON, IOWA

SINGLE HOG-FEEDING TROUGH

Application filed March 21, 1929. Serial No. 348,809.

The present invention relates to improvements in hog feeding troughs, and has for an object to provide a trough so constructed and arranged as to provide for simplicity in 5 the attachment and removal of the trough from a partition, fence or other support, whereby the removal of the trough for cleaning may be expedited.

Another object of the invention is to provide 10 an improved hog trough, so constructed and arranged with reference to its support and the fastening means for removably holding it to the support that it will resist upsetting by the animals.

15 A further object of the invention resides in providing an improved hog trough with novel and improved reinforcements about its upper edge in combination with supporting bars for sustaining the same in place.

20 With the foregoing and other objects in view, the invention will be more fully described hereinafter, and will be more particularly pointed out in the claims appended hereto.

25 In the drawings, wherein like symbols refer to like or corresponding parts through the several views,

Figure 1 is a perspective view of an improved hog feeding trough constructed in 30 accordance with the present invention, with the support indicated in dotted lines.

Figure 2 is a longitudinal vertical section taken on the line 2-2 in Figure 1.

Figure 3 is a cross section taken on the 35 line 3-3 in Figure 2, and

Figure 4 is also a cross section taken on the line 4-4 in Figure 2.

Referring more particularly to the drawings, I have shown in dotted lines in Figure 40 1 and in full lines in the remaining figures a partition, fence or other support 5, in which I make preferably two openings 6 to receive the supporting bars of the trough and trough fastening means.

45 The trough 6 is constructed of sheet metal or other appropriate material cut and shaped to provide a bottom 7, end walls 8, a sloping front wall 9 and a straight or vertical rear wall 10 adapted to lie flush against the partition 5. The upper ends of the side walls 8

are reinforced by angle iron bars 11, the vertical flanges of which are placed against the outer surfaces of the end walls 8 and are riveted or secured thereto by any appropriate form of fastening 12. The end walls 55 8 are provided with upwardly extending portions which are bent over about the horizontal portions of the angle irons 11, as indicated at 13 and are clinched beneath the outer ends of the angle irons, as indicated at 14. 60 This construction serves to take this strain off the rivets 12 and to bind the trough and the angle bars 11 more closely together into a strong and rigid structure, which is desirable as the trough takes its support from 65 the angle bars 11, which as clearly shown in Figures 1 and 3 are extended backwardly for a considerable distance beyond the rear wall 10 to enable the extended portions of said angle bars to project through the opening 6 70 in the partition 5.

Now the upper edge of the front wall 9 is also reinforced by a metallic or other stiffening band 15. This band is placed against the outer face of an upper vertical rim portion 16 of the front wall and an upwardly extended portion of the front wall is bent over and down upon the band 15 as indicated at 17 forming a substantially U-construction. The terminal edge 18 is bent over beneath 75 the band 15 to prevent the band from falling down. The terminal ends 19 of the band, as shown in Figure 3, are overlapped upon the forward ends of the vertical flanges of the angle irons 11 and secured thereto as by the 80 rivets 20. Adjacent this rivet connection, horizontal flanges of the angle irons and adjacent portions of the parts 13 and 14 are cut off, as indicated at 21 to provide a bevel corner. The upper edge of the rear wall 10 85 is also provided with a projecting portion 22 which is folded over downwardly and rearwardly upon the rear face of the wall 10, and it presents a smooth upper edge and also reinforces said edge.

The rearwardly projecting portions of the angle bars 11 are provided with rivets or other forms of headed pivot pins 23, which project toward one another and are upon the vertical flanges. These headed pivots 90 100 ex-

tend through elongated slots 24 made in the latch members 25.

It will be noted that the corner portions 26 of the latch member are rounded off or beveled and that the slots 24 extend close to one end of the latch member but terminate only a short distance past the longitudinal center of the member.

In the use of the device a trough so constructed is applied to the support as indicated in Figure 1, the latch members 25 being arranged as shown and extending longitudinally of the supporting bars 11, so that they may with the bars pass through the openings 6 in the support 5.

In Figure 3 the trough is shown as having been moved into place with the supporting bars 11 projecting through the opening 6 in the support. The blank end portions of the latch members 25 project rearwardly and form convenient hand holds by which the catches may be grasped between the thumb and first finger and pulled rearwardly, the slot 24 traveling on the pivot pin 23 until the end of the slot reaches the pivot pin; whereupon the latch members 25 may be rotated upon the pivot pin to a substantially vertical position, the removed corner portions 26 permitting of a freedom of pivotal movement, until the latch members reach a substantially vertical position. They may then be permitted to fall to the position shown in Figure 4, the other end of the slot 24, by engagement of the pivot 23, holding portions of the latch member above and below the supporting bar 11, so that it may engage the rear side of the partition above and below the pivot point, and thus firmly hold the trough in position upon the support and also avoid any rotational movement of the latch member such as might casually unlatch said member. However, the handhold blank portion of the latch member is disposed upwardly and within convenient reach whenever it is desired to remove the trough for purposes of cleaning. This removal is accomplished by grasping the latch member, rotating it to the position shown in Figure 3, and then simply pulling the trough outwardly from the partition.

It will be appreciated that I have provided a rigid, strong construction of hog feeding trough and fastening means therefor, which will permit of the ready removal of the trough for cleaning, but will hold it in position, so as to avoid its upsetting by the animals in use.

It is obvious that various changes and modifications may be made in the details of construction and design of the above specifically described embodiment of this invention without departing from the spirit thereof, such changes and modifications being restricted only by the scope of the following claims.

What is claimed is:—

1. An improved hog feeding trough comprising a trough body having a substantially vertical rear wall, supporting bars extending across the ends of the trough and rearwardly beyond the rear wall for insertion through holes in a wall or the like, said trough having extension portions folded about said bars for suspending the trough therefrom, and fastening means carried on the extending rear portions of said bars for engaging the remote side of the support to hold the trough thereto. 70

2. An improved hog feeding trough comprising a bottom, end walls having extensions on their upper ends, a substantially vertical rear wall, and a front wall, a pair of angle bars extending across the upper portions of said end walls, said extensions of the end walls being folded about said angle bars and clinched thereon for suspending the trough from the angle bars, a reinforcement for the upper edge of the front wall secured to said angle bars, said bars projecting rearwardly from the rear wall, and fastening means on the angle bars for co-operating with a support. 75

3. A hog trough, comprising a trough body, a pair of end bars secured across the ends of the trough body near the top thereof and extending rearwardly from the trough body for engagement through holes in a support, and an elongated latch member pivoted on the rear end portion of each bar and being of a width less than and of a length greater than the size of said hole in the support, each latch member having a longitudinal slot in one end for the pivot thereof and adapted to be swung and shifted into longitudinal parallel relation with the bar for insertion therewith through said hole and to be subsequently swung and shifted into crosswise relation upon the bar and against the back of the support to secure the trough thereto. 95

In testimony whereof I affix my signature.
